UNITED STATES PATENT OFFICE.

LUCIAN D. FARRIS, OF BRONX, NEW YORK.

CHANGEABLE CHARACTER SIGN.

Application filed July 20, 1927. Serial No. 207,237.

The present invention relates to changeable character signs, and more specifically to such signs having more than one row of characters, and aims to provide certain improvements therein.

An object of the invention is to provide an improved advertising sign of the general type employed by theatres either in front or within the lobby thereof to display the titles of current or future attractions.

Another object of the invention is to provide a sign of the type described so constructed as to be equally well adapted for use with opaque or translucent characters and wherein the insertion, removal or change of the characters can be accomplished with great facility and little expenditure of time.

A still further object of the invention is to provide a sign of the type described wherein in each character although formed on a flat element or blank will when mounted in the sign be draped with an independent frame and thereby add greatly to the effectiveness of the sign as a whole.

The foregoing and other objects of the invention I accomplish by forming the sign with a main frame having one or more rows of character receiving and supporting means and a supplemental frame likewise having character receiving and supporting means, both of said frames being adapted to have the characters insertable into and removable from the top of the row in which they are placed from in front of the sign. The supplemental frame is made movable relatively to the face of the main frame whereby access may be had to said supplemental frame for the purpose set forth. Preferably, the relative movement between the supplemental frame and the main frame is provided by hingedly mounting the former upon the latter so that the supplemental frame may be swung out of the plane of the main frame. The invention also includes other features of novelty which will be hereinafter more fully described.

An embodiment of my invention is shown in the accompanying drawings wherein:

Figure 1 is a front elevation of the sign.

Fig. 2 is a transverse section taken along the line 2-2 of Fig. 1.

Fig. 3 is a greatly enlarged view corresponding to Fig. 2 showing the relative positions of the frames at the time of changing the characters therein.

Fig. 4 is a section taken along the line 4-4 of Fig. 1.

Referring to the drawings, let A indicate the main frame of the sign, which frame consists of top and bottom horizontal elements or rails B, and the upright elements or stiles C. Extending across the frame midway between the rails B is a supplemental rail D, which divides the frame into two sections or panels of equal dimensions. The frame A may be of any construction and material and preferably is formed of wood, the front face of which may be ornamented to give it a pleasing appearance.

Mounted at the rear of the upper panel of the frame A are means for receiving and holding the removable character bearing elements or blanks E in juxtaposition so as to be visible from the front of the panel. These means comprise a supporting member F mounted at the rear of the rail D which serves as the supporting base for said elements E, horizontally extending strips GG secured respectively to the back of the top rail B and intermediate rail D and equally spaced I-elements H secured to the strips G so as to provide slideways for accommodating the elements E.

Connected to the lower rear edge of the frame A by hinges J is a supplemental frame K formed of horizontal strips G', G' and I-elements H' corresponding in dimensions and arrangement with the elements G, G and H respectively of the upper panel of the main frame and adapted to also receive and hold character bearing elements or blanks E. The supplemental frame K is of a size to substantially coincide with the lower panel of the main frame so that when in contact with the rear face of said panel it will support the elements E in a plane common to the plane of said elements mounted at the rear of the upper panel. Preferably, the means for holding the elements E are conveniently made of sheet metal, although bar, rolled stock, wood or the like may be used. The supplemental frame K may be reinforced at its upper and lower edges by angle elements M, M' and suitable means such as a latch N carried by the supporting member F may be employed to hold the supplemental frame K against the rear face of the main frame A.

The frame A may be mounted in any convenient manner so as to provide access to

- its rear in order to insert or remove the elements E therefrom. As herein shown, said frame is mounted upon a metallic casing O by means of hinges P connecting the lower edge of the frame to the lower edge of the casing in a manner such that the frame A may be swung outwardly from the casing. A chain Q or other suitable means may be employed to limit such outward movement. 10 Also, any suitable means may be employed to hold the frame A in its vertical or upright position within the angular flanged portion o of the casing O.

Where the character bearing elements E are of an opaque nature, it will be apparent that a casing such as O may be dispensed with and the frame mounted directly upon a molding or the like. However, where the elements E are of a translucent character so 15 that they may stand forth clearly when viewed from in front of a source of light, the casing O is conveniently provided with a plurality of electric lamps or bulbs R.

When it is desired to change the wording 20 of the sign to announce a change in the program the main frame A is swung outwardly in front of the sign as shown in dotted lines in Fig. 2 to its limit of movement controlled by the chain Q, the latch N 25 is released and the supplemental frame K then moved rearwardly toward the casing O as shown in full lines in Fig. 3. The frames A and K in these angular relative positions permit the ready withdrawal and reinsertion 30 of the elements E from the top of the respective frames to provide the change in the announcement desired to be made. When the change has been made the frame K is again moved outwardly against the frame A and 35 latched thereto and the frame A in turn is returned to its upright position against the front of the casing O and there latched.

From the foregoing description it will be apparent that I have provided a changeable 40 character sign possessing all the advantages and accomplishing the numerous objects hereinbefore set forth, and although said description and drawings make reference to a preferred embodiment of my invention I desire 45 it to be understood that modifications of the specific structure described may be resorted to without departing from the spirit of my invention.

What I claim is:

- 55 1. A changeable character sign comprising a frame divided into two superposed horizontal panels, means carried by the frame for holding character bearing elements or blanks in juxtaposition in a common plane to be visible from the front of the panels, said means being disposed in two rows corresponding to the panels in

the frame, one of said rows of holding means being supported by a supplemental frame which is hingedly mounted on the main frame and adapted to be moved angularly relatively thereto the other row of holding means being supported by means carried by the main frame and forming a closure for the top of the supplemental frame when the 65 rows are in superposed relation, and character bearing elements or blanks insertable into and removable from any of the rows in the frame through the top of said row when the frame and supplemental frame are 70 angularly disposed relatively to each other.

2. A changeable character sign comprising a main frame divided into two superposed horizontal panels, a supplemental frame carried by and relatively movable to 80 the main frame and of substantially the same size as one of the panels, means carried by each of the frames for holding character bearing elements or blanks in juxtaposition to be visible from the front of 85 the panels, the supporting means for the character bearing elements of the upper frame providing a closure for the top of the lower frame when said frames are in superposed relation and uncovering the top of 90 said lower frame when said frames are disposed relatively to each other, and character bearing elements or blanks insertable into and removable from either frame through the top thereof when the main frame and 95 supplemental frame are disposed relatively to each other.

3. A changeable character sign comprising a support, a main frame hingedly mounted at its lower edge to said support 100 and adapted to swing outwardly in front of said support, a supplemental frame carried by said main frame and hingedly connected at its lower edge to the lower rear edge of the main frame and adapted to swing rearwardly toward the support when the main 105 frame is in its outwardly swung position, said main frame being divided into two superposed horizontal panels, the lower of which substantially coincides with the supplemental frame and means at the rear of said frames for supporting character bearing elements in a manner to be visible from the front of the panels, the supporting means for the character bearing elements 110 visible through the upper panel normally providing a closure for the top of the supplemental frame, which top is uncovered when the supplemental frame is swung on its hinge relatively to the main frame. 120

In witness whereof, I have hereunto signed my name.

LUCIAN D. FARRIS.
